UNITED STATES PATENT OFFICE.

MAX SOLOMON FINLEY, OF INDIANAPOLIS, INDIANA.

VEHICLE-TOP.

1,296,062.

Specification of Letter Patent. Patented Mar. 4, 1919.

Application filed September 29, 1917. Serial No. 194,004.

To all whom it may concern:

Be it known that I, MAX SOLOMON FINLEY, a citizen of the United States, residing at Indianapolis, in the county of Marion and 5 State of Indiana, have invented certain new and useful Improvements in Vehicle-Tops, of which the following is a specification.

The present invention relates to vehicle tops, preferably those for automobiles, and 10 one of the primary objects is to provide a foldable top that is automatically extensible eliminating the necessity of manual operation and adjustment.

Another and important object is to provide 15 an effective protector for the top when the same is in folded condition.

Still another object is to provide side curtains and mechanism by which said side curtains can be automatically connected to 20 the top when the latter is in its collapsed condition and extended with said top.

An embodiment of the invention is illustrated in the accompanying drawings, wherein:—

25 Figure 1 is a view partially in section showing the top and side curtains extended.

Fig. 2 is a sectional view illustrating the top in collapsed or folded condition, with the cover removed to avoid confusion.

30 Fig. 3 is a plan view of Fig. 2.

Figs. 4 and 5 are small views of diagrammatic character illustrating the top respectively in extended and folded condition.

Fig. 6 is a detail sectional view illustrating 35 the connection between one of the side curtains and the top.

Fig. 7 is a detail view at right angles to Fig. 6.

Fig. 8 is a view in elevation of the front 40 portion of the top and one of the side curtains when set up or extended.

Fig. 9 is a detail view of one of the controlling latches, and

45 Fig. 10 is a diagram illustrating the electrical circuits that may be employed for the controlling latches.

Similar reference numerals designate corresponding parts in all the figures of the drawings.

50 In the embodiment disclosed, a portion of the body of the vehicle is shown, and is designated 11. It will be understood that this may be of any well known or desired character. The top consists of a frame pref-

55 erably constructed as follows: A main bow

12 is employed having the lower ends of its side arms pivoted to the body, as illustrated at 13. Pivoted to the side arms of the main bow 12, at 14, is a second bow 15. A third bow 16 is disposed in advance of the bow 15, when the top is extended, and a fourth or front bow 17 is also employed that extends beyond the bow 16. Links 18 are pivotally connected at their front ends, as shown at 19, to the rear ends of the bow 17. 65 The central portions of these links are pivoted as illustrated at 20 to intermediate portions of the bow 16, and the rear ends of said links 18 are pivoted at 21 to the upper portions of the second bow 15. The said links 70 18 carry at their rear ends rearwardly projecting hooks 22. The rear ends of the third bow 16 are pivotally connected to the front ends of links 23, said links being pivoted at their rear ends, as shown at 24, to 75 the upper portions of the main bow 12. Links 25 are pivoted at their front ends, as shown at 26, to intermediate portions of the front bow 17 and have their rear ends pivoted as shown at 27 to the upper or 80 forward portions of the bow 16. The distance between the pivots 26 and 27 is substantially the same as the distance between the pivots 19 and 20. Another set of links 28 are pivoted at their front ends to ears 85 29 rigidly carried by the second bow 15 and are pivoted at their rear ends, as shown at 30, to intermediate portions of the links 23. At the lower ends of the bows 12 are fixed offset fingers 31 to which are pivoted as 90 shown at 32 the lower ends of links 33 that are pivotally connected to the side arms of the second bow 15, as shown at 34 adjacent to the pivots 14.

This frame carries a suitable cover 35 at- 95 tached at its front ends to the front portion of the bow 17, and at its rear end to the upper end of a case or envelop 36. This case or envelop is preferably of sheet metal, having end walls 37 and a rear wall 38, the 100 front being open. The upper end of the main bow 12 is located in the upper rear corner of the case 36, to which it is suitably pivoted, as indicated at 39. The lower portion of the case is also provided with guide- 105 ways, preferably in the form of curved slots 40, in which are engaged pins 41 carried by the body. As illustrated in Fig. 2, the top is collapsible wholly within the case, and said case, by reason of its mounting, will 110

assume a substantially horizontal position when the top is folded therein. For the purpose of automatically extending said top, coiled springs 42 are employed connected at 5 their front ends to the hooks 22 of the links 18, and having their rear ends connected as illustrated at 43 with the rear portions of the links 28. These springs are powerful enough to automatically raise the top from 10 its collapsed position as illustrated in Fig. 2, and extend it to the condition shown in Fig. 1. To prevent this automatic action, latches are employed that engage the front bow 17 to secure the top in its collapsed condition. 15 These latches comprise electro-magnets 44 mounted on the end walls 37 of the case 36 and having sliding armatures 45 that engage in suitable sockets 46 formed in the bow 17, as shown in Fig. 10, or otherwise engaging 20 said bows as may be desired. The electro-magnets are included in a circuit 47 that also includes a suitable source of electrical energy 48 and a controller switch or button 49 that is located at the front of the car in 25 convenient relation to the operator. It will thus be evident that if the top is in collapsed condition, all that is necessary to raise and extend it is for the operator to close the circuit, whereupon the electro-magnets will be 30 energized, thus causing their armatures to be withdrawn into the same. This, by releasing the top, permits the springs 42 to operate and extend the same to the condition shown in Fig. 1.

35 Within the corners of the case 36 are located curtains 50 mounted on ordinary spring rollers that are journaled, as shown at 51 in said case. These curtains may be provided with any desired arrangement of 40 flexible windows and doors 52. They are provided at their front ends with arms 53 pivoted, as shown at 54, and engaged by coiled springs 55, surrounding the pivots. These springs serve to swing the arms upwardly when the top is in folded condition, 45 as shown in Fig. 2. The free ends of the arms are provided with eyes 55^a arranged to engage over pins 56 carried by the front bow 17. The arms, however, are normally held 50 against this swinging movement by latches in the form of plunger armatures 57 operating in electro-magnets 58, the said magnets being mounted on the inner sides of the end walls 37 of the case 36 in a position to hold 55 the arms depressed, as indicated in Fig. 2. The electro-magnets 58 are in a circuit 59, which includes the source of electrical energy 48 and also a circuit controller 60 suitably located in the front of the vehicle, 60 where it is convenient to the operator of said vehicle.

As already explained, the top when collapsed, folds within and is housed by the case 36, and the upper or outer portion of 65 this case is then covered by a closure 63 of

sheet material that extends across the front portion of the bow 17, and fits over the upper or outer portion of said case.

With this construction, it will be evident that if it is desired to extend the top without 70 the side curtains, the closing of the circuit 47 by the controller 49 will effect this operation as already described. If, however, the side curtains are to be utilized, the operator first closes the circuit 59 by means of the 75 controller 60. This energizes the electro-magnets 58, causing the withdrawal of the latches 57. The arms 53 are thus released and will swing to positions with the eyes engaged over the pins 56. If now the circuit 80 47 is closed the top being released, will be automatically elevated and the curtains carried along with it. The front ends of these curtains may then be moved to closed position with respect to the wind shield 61, to 85 which they may be attached by suitable fasteners indicated at 62 in Fig. 8.

From the foregoing, it is thought that the construction, operation and many advantages of the herein described invention will 90 be apparent to those skilled in the art without further description, and it will be understood that various changes in the size, shape, proportion and minor details of construction may be resorted to without departing from 95 the spirit or sacrificing any of the advantages of the invention.

Having thus fully described my invention, what I claim as new, and desire to secure by Letters Patent, is:—

1. In a structure of the character set forth, the combination with a vehicle, of a swinging case mounted on the rear portion of the vehicle, an extensible top for the vehicle, comprising a cover, and a collapsible frame, 100 the cover and frame being foldable into the case and depressible therewith, said frame including a bow pivotally mounted on the vehicle and also having a pivotal mounting in the upper portion of the case.

2. In a structure of the character set forth, the combination with a vehicle, of an extensible and rearwardly foldable depressible top therefor, including a rear bow pivotally mounted on the vehicle and swinging rearwardly to a depressed position, a relatively rigid case for the top having the upper portion of the bow housed therein and pivoted thereto, said case having curved guideways, and guiding elements on the vehicle engaged 115 in the guideways.

3. In a structure of the character set forth, the combination with a vehicle, of a rearwardly collapsible and forwardly extensible top therefor; a swinging case for receiving the top when collapsed, and roller curtains mounted within the case and swinging therewith.

4. In a structure of the character set forth, the combination with a vehicle, of a rear-

- wardly collapsible and forwardly extensible top therefor, a swinging case for receiving the top when collapsed, roller curtains mounted within the case and swinging therewith, and means for detachably connecting the curtains to the top when the latter is collapsed to cause their extension with said top.
5. In a structure of the character set forth, the combination with a vehicle, of a swinging support at the back of the vehicle, extensible curtains carried by the support, an extensible and collapsible top for the vehicle movable toward and from the support, and means for detachably connecting the curtains to the top when both are collapsed to effect their simultaneous extension and to permit the extension of the top without extending the curtain.
6. In a structure of the character set forth, the combination with a vehicle, of an automatically extensible top therefor, side curtains, and means for automatically connecting the side curtains to the top to effect their movement simultaneously therewith.
- 25 7. In a structure of the character set forth, the combination with a vehicle, of an automatically extensible top therefor, side roller curtains, latches for automatically connecting the side curtains to the top to effect their movement simultaneously with the top and to permit the extension of the top independently of the curtains, and means for controlling the action of the latches.
8. In a structure of the character set forth, the combination with a vehicle, of a swinging case mounted on the rear portion thereof, an extensible top collapsible into the case, roller curtains located in the case, latches for connecting the curtains to the top to permit the simultaneous movement of the same, electrical devices for holding the latches in inactive positions, and electrical means for
- 20 10 15 20 25 30 35 40

actuating the holding devices, including a controlling device at the front of the vehicle.

9. In a structure of the character set forth, the combination with a vehicle, of a swinging case mounted on the rear portion thereof, an extensible top movably mounted on the vehicle and collapsible into the case, and a cover for the case carried by the front portion of the top and separate from the case, said cover being movable with the top to a position across said case over said top when the latter is collapsed therein.

10. In a structure of the character set forth, the combination with a vehicle, of a swinging case mounted on the rear portion thereof, an extensible top movably mounted on the vehicle and collapsible into the case, said top including a front bow, and a cover for the case carried by the front bow and extending across said case over the top when the latter is collapsed in said case.

11. In a structure of the character set forth, the combination with a collapsible and automatically extensible top, of means for constantly urging the top to its extended condition, a latch for holding the top against such movement, means for actuating the latch, including a controller in the front of the vehicle, side curtains, automatic latches for connecting the side curtains to the top when the latter is in its collapsed condition, means for holding the latches in inactive position, and operating mechanism for said means, including a controller located at the front of the vehicle.

In testimony whereof I affix my signature in the presence of two witnesses.

MAX SOLOMON FINLEY.
